P. C. ICKES.
KNOCKDOWN TANK.
APPLICATION FILED NOV. 21, 1916.

1,289,469.

Patented Dec. 31, 1918.

UNITED STATES PATENT OFFICE.

PETER C. ICKES, OF CHANUTE, KANSAS.

KNOCKDOWN TANK.

1,289,469.

Specification of Letters Patent. Patented Dec. 31, 1918.

Application filed November 21, 1918. Serial No. 182,683.

To all whom it may concern:

Be it known that I, PETER C. ICKES, a citizen of the United States, residing at Chanute, in the county of Neosho and State of Kansas, have invented certain new and useful Improvements in Knockdown Tanks, of which the following is a specification.

This invention relates to an improvement in knockdown tanks, and perhaps more particularly to the type of tank as illustrated in Patent No. 1,019,255, granted to me on March 5, 1912, and over which device the present tank is an improvement.

An object of my invention is to provide a knockdown tank which has the top and bottom portions thereof each composed of a plurality of sections to be built up and connected together thus providing a structure which is more readily handled and is also more cheaply manufactured as standard sizes of sheet metal may be used in the formation of the various sections forming the top and bottom portions.

A further object resides in making the various sections of the top and bottom portions substantially sector shape where a round or circular tank is to be constructed, these top and bottom sections being thus so formed that two or more sections may be cut from a single sheet of material and a very small percentage of waste will occur.

Yet another object is to eliminate the angular ends of the substantially sector shaped members and to provide a closing member for the space which would otherwise be left so that an end member is provided for the tank which is liquid tight over its entire extent.

With the above and other objects in view, my invention consists in certain novel features of construction and combinations of parts which will be hereinafter set forth in connection with the drawings and then more particularly pointed out in the claims.

45 In the drawings:—

Figure 1 is a view in side elevation of a tank constructed after the manner of my invention.

Fig. 2 is a fragmentary view in elevation to show the construction of the bottom of the tank.

Fig. 3 is a view similar to Fig. 2 showing the top construction.

Fig. 4 is a perspective view showing one of the plates used in the construction of the top of the tank.

Fig. 5 is a perspective showing one of the bottom plates.

Fig. 6 is an enlarged detail sectional view through the securing flanges of a pair of the plates used in the formation of the top and bottom of the tank.

Fig. 7 is an enlarged detail sectional view to show the manner of securing the side wall sections together and the top and bottom members in place thereon.

The side wall of the tank is built up of a number of curved plates 1 which have the flanges 2 at the side edges and flanges 3 at the end edges, and these plates are curved throughout their transverse extent to such a degree that when brought together with the edge flanges abutting they form a cylindrical tank.

The bottom member for the tank is made up of a plurality of substantially sector shaped plates 4, one of which is better shown in Fig. 5, and as is here illustrated the plates 4 have the flanges as indicated at 5 and 6 bent up on the angularly disposed edges 80 thereof, the extreme angular point of the sector shaped plates being preferably dispensed with and a flange 7 being formed at this end having the lesser transverse extent. The flanges 5 and 6, and the flange 7 are provided with bolt receiving openings as indicated at 8, and in the setting up of the top member the several plates 4 are assembled in the proper fitted relation, it being preferable that the packing strips 9, which can be of water proof felt or other suitable material, be placed between the flanges 5 and 6. The reinforcing members 10, which are preferably made of lengths of channel iron are bent at their ends to provide the outstanding flanges 11, and these reinforcing strips have bolt receiving openings formed therethrough in such spaced apart relation that these bolt receiving openings are in registry with the openings 8 of the flanges 5 and 6, and then by passing the bolt 12 through the registering openings of the strips and flanges and tightening the nuts 13 thereon, the flanges 5 and 6 are drawn up against the packing strip 9 and 10, thus a tight and liquid proof joint is formed.

The upturned end flanges 7 of the plates 4 are curved throughout their transverse extent, and thus a circular opening left in the center of the bottom member has a rim flange 5 formed therearound by these curved flanges 7. The extending ends 11 of the reinforcing strips 10 have bolt receiving openings formed therein and registering openings are formed through the flanges 7. A circular 10 closing member 14 has a flange as indicated at 15 formed around the edge thereof and provided with bolt receiving openings which register with the openings of the extensions 11 and the flange portions 7, and by passing 15 the clamping bolts 16 through these registering openings of the several members and tightening nuts on the ends thereof, the parts are drawn together in such relation that a tight joint is established, it being 20 preferable that the packing strip 17 be disposed between the flanges 7 and the flange 15. This assemblage of the several members 4 and the member 14 forms a bottom member which is to all intents and purposes substantially continuous and liquid tight 25 throughout its entire extent, it however being understood that the formation of the member from a plurality of panels or members permits the formation of a completed 30 bottom or top having a considerable surface area and a large diameter, without the necessity of procuring a single sheet of material which would in some instances necessarily be of special and extra large sizes, and 35 also with economy in the sheet material which is used as the substantially sector shaped panel members can be cut from opposite ends of a sheet and thus very small waste of the material will occur.

The top portion of the tank is constructed somewhat after the manner of forming the bottom portion, the several substantially sector shaped plates or panels 18 being provided with the side flanges 19 and 20, as is 40 better shown in Fig. 4, and being cut off at their ends as indicated at 21, so that the extension 22 is left. The flanges 19 and 20 are provided with bolt receiving openings 23 and by assembling the parts in such 45 relation that a plurality of the plates or panels 18 are made to form a circular top portion and disposing the strengthening strips 24 on the outer sides of the flanges 19 and 20 with the clamping bolts 25 50 clamped and secured therethrough, the several panels will be held together in the proper fitted relation. It is preferable that the packing strip 26 be placed between the flanges 19 and 20 of the several panels 18, and thus when the flanges are clamped together through the medium of the bolts 25 55 a liquid tight joint is established. The extensions 22 project inwardly beyond the flanges 19 and 20 and also beyond the 60 strengthening strip 24, which in the present

instance are preferably made straight and without the flange extensions 11 such as are provided on the reinforcing strips 10, and these extensions have the bolt receiving openings 27 provided therethrough. A plate 28 70 is made of such size that it may be fitted over the extensions 22 of the several panels 18 and then by passing the clamp bolts 29 through this plate and through the openings 27 and securing nuts thereon, the plate 75 will be secured in the proper position to close the opening at the center of the top portion. It is preferable that a packing strip or ring be placed between the plate 28 and the extension 27, and also this plate is 80 preferably provided with the hand hole or opening 30.

As has been stated, the several side wall members 1 have the end flanges 3 provided thereon, and these end flanges are preferably provided with bolt receiving openings, similar openings being provided in registering relation through the several panels 4 and 18 which make up the bottom and top portions of the tank. The packing 85 rings 31 are placed upon the end flanges 3 and then by fitting the bottom and top portions in place and securing the same by means of the clamp bolts 32, the bottom and top portions are not only secured in the proper closing position, but also liquid tight 90 joints are provided. The reinforcing strips 33 have end extensions as indicated at 34 and 35 and these reinforcing strips 33 are provided with spaced apart bolt receiving 100 openings, the flanges 2 at the sides of the plates 1 being provided with registering openings. In assembling the side members previous to the fitting of the top and bottom portions thereon, the packing strips 36 are 105 fitted between the adjacent side flanges 2 and with the reinforcing strips 33 placed against the outer sides of these flanges, the clamp bolts 38 are inserted and tightened 110 through the bolt receiving openings to thus bear against the reinforcing strips and secure the plates 1 in rigid mounting at their side edges. The extensions 34 and 35 are provided with bolt receiving openings which 115 register with certain of the openings through the end flanges 3 and through the top and bottom portions, and thus as the clamp bolts 32 are fitted in place, certain of these bolts will be passed through the extensions 34 and 35 and consequently the reinforcing strips 120 will be secured at their ends.

From the foregoing it will be seen that I have provided a liquid storage tank which is so constructed that it may be filled up 125 from a plurality of members formed from sheet metal and so arranged that a tank of large dimensions may be constructed from metal sheets of standard sizes, and that through the construction of the tank as is above set forth, the tank may be shipped in 130

knockdown form and may then be assembled at the point at which it is to be used by unskilled labor, the only essential point being that the packing strips shall be properly fitted and the several members of the tank construction be assembled and erected in the proper relation.

While I have herein shown and described only one specific form of the tank and have set forth only certain arrangements of the parts, it will be understood that strap metal reinforcing strips might be employed, that the construction as described for the top member might be used in conjunction with the bottom of the tank, and that other changes and modifications might be resorted to in the form and arrangement of the several parts without departing from the spirit and scope of my invention, and hence I do not wish to be limited to the exact disclosure, but rather only to such points as may be set forth in the claims.

I claim:

1. A tank including with a substantially cylindrical body portion open at its ends, a plurality of plates of substantially truncated sector-shape having flanges provided along the angularly disposed edges thereof and across the narrow end, means by which the several sector-shaped plates are connected together at the side flanges and are thus assembled to provide an end portion for the body of the tank which end portion has a central opening therein with a flange upstanding around the opening, a substantially circular closing member having a flange around the edge thereof shaped to be fitted

within the opening of the end member, and means to secure the closing member in the fitted position.

2. A tank including with a substantially cylindrical body portion open at the ends, a plurality of substantially sector-shaped plates having the pointed ends thereof cut away, side flanges provided along the angularly disposed edges of said members and the narrow ends thereof being formed to provide for reception of a closing member, said side flanges having openings provided therethrough to register when the members are fitted together, reinforcing members fitted on the flanges and having openings lining up with the openings of the flanges, fastening means passed through the openings of the reinforced members and of the flanges to connect the several plates together in an arrangement to substantially close one of the ends of the cylindrical body portion and which end member has a circular opening in the center thereof, means to secure the assembled end member upon the body portion, a circular closing plate to be fitted to cover the opening left at the center of the end portion and having portions thereof provided to fit with the securing portion thereof, and fastening means by which the closing plate is held in the secured position.

In testimony whereof I affix my signature in presence of two witnesses.

PETER C. ICKES.
